(57) **CLAIM**

The ornamental design for a valve remover with storage volume, as shown and described.

DESCRIPTION

FIG. 1 is a first perspective view of a valve remover with storage volume according to one embodiment of the invention.

FIG. 2 is a left side view of the valve remover with storage volume of FIG. 1.

FIG. 3 is an end view of the valve remover with storage volume of FIG. 1.

FIG. 4 is an opposing end view of the valve remover with storage volume of FIG. 3.

FIG. 5 is a right side view of the valve remover with storage volume of FIG. 1.

FIG. 6 is a front side view of the valve remover with storage volume of FIG. 1; and,

FIG. 7 is a back side view of the valve remover with storage volume of FIG. 1.
